INSULATOR

John J. Taylor, Barberton, Ohio, assignor to The
Ohio Brass Company, Mansfield, Ohio, a cor-
poration of New Jersey

Application February 2, 1933, Serial No. 654,859

4 Claims. (Cl. 173—318)

This invention relates to electric insulators and particularly to insulators for supporting relatively high mechanical loads for extended periods of time without danger of failure.

5 One object of the invention is to provide an insulator having relatively high mechanical strength and long life, and which will not be injuriously affected by temperature changes.

10 A further object of the invention is to provide an insulator which shall be of improved construction and operation.

Other objects and advantages will appear from the following description.

15 The invention is exemplified by the combination and arrangement of parts shown in the accompanying drawing and described in the following specification, and it is more particularly pointed out in the appended claims.

In the drawing:

20 Fig. 1 is an elevation with parts in section showing one embodiment of the present invention.

Fig. 2 is a fragmentary section on line 2—2 of Fig. 1.

25 Figs. 3, 4, 5 and 6 are elevations of the upper ends of modified forms of pins for use in connection with the insulator.

Dielectric material such as porcelain, commonly used for insulators, has high mechanical strength in compression but is relatively weak 30 in tension and shear. The present invention contemplates the support of the load on the insulator largely by compression on the dielectric member. This is accomplished by providing the fittings with opposed surfaces which tend 35 to compress the dielectric material between them.

In the form of the invention shown in Fig. 1, the numeral 10 designates the dielectric member made of porcelain or other suitable material having an attachment head provided with 40 a recess for receiving a pin 11. The inner end of the pin is divided into a plurality of steps; one of the steps having a conical bearing surface 13, and the other step having conical bearing surfaces 14 and 15 disposed at different angles 45 relative to the axis of the pin. The pin also carries a resilient flange 16. The pin is secured in a recess in the dielectric member by cement 17 and the entire outer surface of the pin is coated with wax or otherwise treated to prevent bonding between the pin and the cement. The cement is bonded to the inner surface of 50 the recess in the dielectric member. The cap 12 is provided with an inclined bearing surface 18; the inside of the cap also being treated to prevent bonding with the cement 19, which

secures the cap to the outer surface of the dielectric member. The cement is suitably bonded to the dielectric member on its outer surface. The cap is preferably provided with a plurality of inwardly extending fins or ribs 20 to facilitate proper location of the cap relative to the dielectric member when the parts are assembled. It will be apparent that the opposed wedging faces of the cap and pin will tend to compress the porcelain and cement disposed between 10 these faces when a load is placed on the insulator.

The porcelain is relatively hard and unyielding as compared to the cement, and the distortion of the porcelain part is negligible. However, the cement will yield under the wedging action of the bearing faces and since the thickness of the interposed cement varies for different positions along the tapered bearing faces, the amount of cushioning effect produced by 20 the cement will differ for different positions on these bearing faces, giving rise to an unequal distribution of the stress on the bearing surface of the porcelain. The cement has a strut action between the metal and the porcelain 25 which transmits the force between these parts. The length of the cement strut at the upper edge of the surface 13, for instance, is less than it is at the lower edge of this surface and for a given movement of the pin 11 downwardly 30 under load, the total compression of the cement strut at the top of the surface 13 will be the same as the total compression at the bottom of the surface; but since the strut at the top of the surface is much shorter than at the bottom 35 of the surface, the force transmitted to the porcelain will be greater at the top of the bearing surface than it will at the bottom, thus tending to concentrate the stress at the upper portions of the wedging bearing surfaces. 40

A similar concentration will be produced at the lower edge of the bearing surface 18 on the cap. The resiliency of the cap will tend to offset this concentration as the lower edge will yield somewhat under the force and will relieve the 45 stress at this point. Moreover, the bearing surface of the cap is much greater than that of the pin, so that the stress at any point over the outer portion of the dielectric member will be less than at the inner portion. 50

In order to effect a distribution of the stress produced by the pin, the wedging bearing surface is divided into a plurality of steps. This will give a much better distribution than a single step having the same total bearing surface as 55

the plurality of steps. A further equalization is secured on the lower step of the pin, shown in Fig. 1, by dividing the step into zones having different angularity. For a given downward movement of the pin 11 under load, the lower zone 15 will compress the cement strut a greater amount than will the upper zone 14 so that the amount of compression is approximately proportional to the length of the cement strut, thus tending to equalize the pressure on the dielectric member.

The conical or wedging bearing faces on the metal fittings not only place the porcelain under compression but also serve to compensate for differential expansion of the dielectric and metal parts, due to temperature changes. When the temperature falls, the load on the pin will tend to draw the pin downwardly until checked by the conical bearing surface. The flange 16 and the cement shoulder below the flange will yield sufficiently to permit downward movement of the pin 16. When the temperature rises, the pressure on the outer face of the dielectric member, produced by the cap, will be relieved and the expansive force of the pin 11 will tend to burst the porcelain. If the frictional engagement between the wedging faces 13, 14 and 15 and the cement were sufficient to prevent return of the pin under the expansive force, injury to the porcelain would be apt to occur.

If reliance were placed entirely upon the lubricating effect of the coating on the surfaces 13, 14 and 15, satisfactory return might occur for a time but the lubricating material is apt to become displaced or lose its effectiveness in time, after which the pin might stick in its socket and a rise in temperature would then be apt to burst the dielectric member. This danger is eliminated by the resilient flange 16, which assists the wedging action of the surfaces 13, 14 and 15 in returning the pin to its upper position when the expansive force increases.

The resilient flange 16 has another important function in the operation of the insulator, and this is to insure an adequate cap reaction before expansive action is produced by the wedging faces of the pin. When a load is placed upon the insulator pin, the initial portion of this load is transmitted by the flange 16 before any substantial wedging action is produced by the conical surfaces of the pin. This tends to draw the dielectric member and its attached cement 19 downwardly in the seat 18 of the cap, producing a cap reaction inwardly on the dielectric member before an outward expansive force is brought to bear. The inward pressure will always be kept in excess of the outward pressure and since the arch of the dielectric member produces a greater resistance to inward pressure than to outward pressure, the balance of pressure is always kept in the right direction.

While the difference in angularity between the steps 14 and 15 improves the distribution of stress, it also produces a direction of stress on the lower face 15 not so advantageous as that of the other faces. The stress produced by the face 15 will be directed downwardly at a steeper angle than that on the faces 13 and 14 and will be transmitted to the portion of the dielectric member below the cap 12 so that there is no abutment portion of the cap for receiving this stress, which consequently tends to produce tension in the dielectric member. The more abrupt angle of the face 15, however, makes possible a deeper

cut above the flange 16 for a given length of bearing surface than would otherwise be secured and this is an advantage because it permits a resilient flange of sufficient width to be located at a higher point on the pin.

The advantage of the deeper notch above the flange 16 may be secured, without the disadvantage of the downwardly directed force from the surface 15, by filling the opening between the flange 16 and the surface 15 with a yielding material 21 which will exclude the cement from this notch, as shown in Fig. 3. This, however, will eliminate the action of the bearing face 15 in transmitting the force of the load to the dielectric member and distributing the load throughout the dielectric material.

The resilient flange may be located still higher on the pin if a radial notch is cut at the lower edge of the bearing surface 14, as shown at 22 in Fig. 4. In this case it is very desirable to exclude cement from the notch 22 by means of a yielding material 23 or other suitable expedient, so as to prevent the radial face at the lower edge of the flange 14 from bearing directly on a cement shoulder. This arrangement is especially advantageous where a second resilient flange 25 is desirable or where more than two bearing steps are provided, as shown in Fig. 5.

In Fig. 5, 3 steps 26, 27 and 28 are shown, and a single resilient flange 29 is located below the bearing steps and separated from them by a notch 22, filled with yielding material 23.

Fig. 6 combines the characteristics of Figs. 1 and 5 in that it provides a plurality of bearing surfaces 30, 31 and 32, these surfaces being disposed at various angles relative to the axis of the pin so as to impart a compression to the cement struts more nearly proportional to the length of the struts. The upper bearing surface 30, for instance, may have an inclination of 20 degrees to the axis of the pin, while the second surface 31 has an inclination of 30 degrees, and the lower surface an inclination of 40 degrees. A resilient flange 16 is provided, as in Fig. 1. With a pin of this kind, the stress will be distributed approximately uniformly over the active portion of the dielectric material and the resilient flange 16 will not only insure establishment of cap reaction prior to expansive force exerted by the wedging pin surfaces under the load on the insulator, but will also insure movement of the pin in its socket to compensate for temperature changes. It will be understood that in all cases the portion of the pin in the cement below the bearing flanges is sufficiently relieved to prevent interference with the action of the bearing faces.

I claim:

1. An insulator comprising a dielectric member having a recess therein, a pin having an attachment head disposed in said recess and provided with a rigid, bearing surface tapered inwardly toward the free end of the pin, said bearing surface having portions disposed at different angles relative to the axis of the pin, the angle of each portion relative to the axis of the pin being greater than the angle of the portion next adjacent thereto toward the inner end of the pin, cement disposed in said recess about said head, and a resilient flange on said pin and engaging said cement and disposed next adjacent to, but spaced from, the portion of said bearing surface having the greatest angle with the axis of said pin, to provide for

5

a deep groove between said flange and bearing surface.

2. An insulator comprising a dielectric member having a recess therein, a pin having a bearing head disposed in said recess, said bearing head having a plurality of rigid, bearing surfaces thereon tapered inwardly toward the free end of the pin, cement interposed about said head within said recess, said pin being unbonded to said cement, one of said bearing surfaces having a less maximum diameter and a greater angle relative to the axis of the pin than another of said surfaces farther within said recess, and a resilient flange secured to said pin and engaging said cement for restoring said pin to its initial position when displaced therefrom said flange being disposed next adjacent, but spaced from, the bearing surface of greatest angle with the axis, to provide a deep groove between said flange and surface.

3. An insulator comprising a dielectric member having an attachment head thereon, a cap enclosing said head, cement interposed between said cap and head, said cap having a conical bearing face, the surface of said cap being unbonded to said cement, a pin having a bearing head disposed in a recess in said dielectric member, said head having a plurality of rigid, bearing faces tapered inwardly toward the free end of the pin, one of said faces having a greater angle relative to the axis of the pin and having a less maximum diameter than another face farther within said recess, cement disposed in said recess about said pin, said pin being unbonded to said cement, and a resilient flange

on said pin spaced from said bearing faces toward the free end of the pin and engaging said cement for transmitting the initial portion of the load on said pin to said insulator to insure initial cap reaction before excessive wedging action is produced by the bearing surfaces of the pin and to facilitate movement of the pin to compensate for differential expansion and contraction due to temperature changes the bearing face having the greatest angle with said axis being next adjacent said flange to provide for a deep groove adjacent said flange.

4. An insulator comprising a dielectric member having an attachment head provided with a recess, a pin having one end thereof disposed in said recess and having a rigid, conical bearing surface tapered inwardly toward the free end of the pin, a cap surrounding said head and having a conical bearing surface opposed to and tapered in the same direction as the bearing surface of said pin, cement securing said cap and pin to said head, said cap and pin being unbonded to said cement, a portion of the bearing surface of said pin having a greater angle relative to the axis of the pin than another portion of said surface farther within said recess, and a resilient flange below and next adjacent to the portion of the bearing surface of said pin having the maximum angle with said axis and engaging said cement to insure initial cap reaction prior to excessive expansive force exerted by the bearing surface of said pin, and to facilitate movement of said pin to compensate for temperature changes.
